(57) **CLAIM**

The ornamental design for a cellular telephone holder, as shown and described.

DESCRIPTION

FIG. 1 is a front perspective view of a cellular telephone holder embodying my new design;
 FIG. 2 is a front elevational view thereof;
 FIG. 3 is a rear elevational view thereof;
 FIG. 4 is a right side elevational view thereof, and the left side elevational view being a mirror image thereof;
 FIG. 5 is a top plan view thereof;
 FIG. 6 is a bottom plan view thereof; and,
 FIG. 7 is a rear perspective view of a cellular telephone holder embodying my new design.
